[57] **CLAIM**

The ornamental design for a unit for removing dust from industrial equipment by substantially increasing air flow, as shown and described.

DESCRIPTION

FIG. 1 is a front perspective view showing the unit for removing dust from industrial equipment by substantially increasing air flow;

FIG. 2 is a rear perspective view thereof;

FIG. 3 is a top plan view thereof;

FIG. 4 is a bottom plan view thereof;

FIG. 5 is an enlarged left end perspective view thereof in one position; and,

FIG. 6 is an enlarged left end perspective view thereof in an alternative position.

The right end of the design is substantially a mirror image of that shown except for the projecting tubes at the top right end.

FIG. 1

FIG. 2

FIG. 3

FIG. 4

FIG.5

FIG.6
